[57] CLAIM

The ornamental design for a hand held electric mixer, as shown and described.

DESCRIPTION

FIG. 1 is a perspective front elevational view of a hand held electric mixer from above, showing my design;
FIG. 2 is a front view of the appliance of FIG. 1;
FIG. 3 is a right-side view of the appliance of FIG. 2;
FIG. 4 is a left-side view of the appliance of FIG. 2;
FIG. 5 is a rear view of the appliance of FIG. 2;
FIG. 6 is a top plan view of the appliance of FIG. 2; and,
FIG. 7 is a bottom plan view of the appliance of FIG. 2.
The broken line showing of part of a power cord is for illustrative purposes only and forms no part of the claimed design.
